UNITED STATES PATENT OFFICE.

MAHLON DUFF GREEN, OF FLORA, ILLINOIS.

CUSPIDOR.

2,97,319.

Specification of Letters Patent.

Patented Oct. 19, 1909.

Application filed December 24, 1908. Serial No. 469,080.

To all whom it may concern:

Be it known that I, MAHLON D. GREEN, a citizen of the United States, and a resident of Flora, in the county of Clay and State of Illinois, have invented a new and Improved Cuspidor, of which the following is a full, clear, and exact description.

This invention relates to cuspidors which may be hermetically sealed for sterilizing purposes.

One object of the invention is to provide a cuspidor having a removable receptacle therein and also means whereby a sterilizing or cleansing fluid may be applied thereto.

A further object of the invention is to provide means whereby a series of cuspidors may be simultaneously cleansed and sterilized.

The invention consists in the construction and combination of parts, to be more fully described hereinafter and particularly set forth in the claims.

Reference is to be had to the accompanying drawings, forming a part of this specification, in which similar characters of reference indicate corresponding parts in all the views, and in which—

Figure 1 is a sectional view taken on the line 1—1 in Fig. 2, with parts broken away and in elevation; Fig. 2 is a sectional view on the line 2—2 in Fig. 1, showing the cuspidor in elevation; and Fig. 3 is a perspective view of the removable receptacle.

The cuspidor comprises a basin 1, having a central depending hollow extension 2 at the bottom thereof. The upper edge of the basin 1 is arranged to fit against a gasket 4 held within a groove 5 formed in the rim of the cover 6. Said cover is provided with lugs 7 which overlie a lug 8 on the basin 1 and through which a pivoting pin 9 is passed. The cover has a central depending projection 10, which is adapted to deflect the sterilizing fluid, as shown by the arrows in Fig. 1. A lug 12 extends from the outside of the cover 6, and to this lug a pair of links 14 are pivoted by means of a pin 15. A handle or cam-faced lever 16 is pivoted at 17 between the links 14, and is adapted to coact with the under side of a lug 18, which projects from the basin 1. By means of the handle 16, the cover 6 may be firmly clamped against the basin 1, and the gasket 4 forms a hermetic seal for the cuspidor.

Extending around the inner surface of the

basin 1 near the top thereof is a ledge 20 which forms a support for the wire ring 21 of the removable receptacle. The body of said receptacle comprises a foraminous body or screen 24 which is fastened to the ring 21 in any suitable manner. A bail 25 is secured to the ring 21 in order that the receptacle may be readily removed from the basin 1 for cleansing purposes.

The basin 1 is secured to a pipe 30 having lateral threaded openings 31 which receive the threaded projections 2. A nozzle 34 is provided with a flange 35 adapted to abut against the end of the pipe 30. A short pipe 36, provided with a flange 37, abuts against the flange 35, and is held in place by a union 38. The nozzle 34 is provided with a discharge opening 40 in line with the axis of the pipe 30, and also with a lateral discharge opening 42 extending into the basin 1. A plurality of cuspidors may be mounted upon a plurality of sections of pipe similar to the pipe 30 and all connected together to form one system.

A valve 44 is mounted on a rod 45, which extends longitudinally within the pipe 30 and is connected at one end 46 with a crank 47 which is journaled in the pipe 36. Said crank is provided with a handle 48, in order that the same may be manipulated from the outside to simultaneously operate a series of valves 44, which control the longitudinal passages of the nozzles 34. The other end 50 of the rod 45 is provided with an eye which is connected to a coiled spring 51 secured to the pipe by means of a bolt 52.

A sterilizing fluid may be supplied through a pipe 55 connected at one end to a valve 56. Said valve 56 is also connected to the pipe 36. A discharge valve 58 may be connected to the other end of the piping system and provided with an elbow or other connection 60, whereby the contents of the system may be discharged.

The operation of the device is as follows:—When it is desired to sterilize or cleanse the cuspidors, the covers 6 are clamped in position upon the basins 1, the handle 48 is turned to the position shown in Fig. 1, so that the valves 44 close the longitudinal passages of the various nozzles. The sterilizing fluid is then admitted by means of the valve 56, said fluid passing through the pipe 36 and nozzles 34 laterally into the cuspidors, as indicated by the arrows in Fig. 1.

- The fluid then passes from the first cuspidor through the pipe 30 and through the next nozzle into the next cuspidor, and from thence out through the bottom of that cuspidor to the next nozzle, and so on through the system. By turning the handle 48 so that the valves 44 are moved away from their seats, the sterilizing fluid may be forced directly through the piping without first passing through the various cuspidors, in order to effectually cleanse said piping and force the contents out through the discharge valve 58 and connection 60, which will then be open.
15. The receptacles 24 may be removed and placed in a suitable sterilizing chamber, if desired, and then be replaced in the cuspidors.

Having thus described my invention, I 20 claim as new and desire to secure by Letters Patent:—

1. The combination of a cuspidor having a hollow extension at its bottom and provided with a cover, and a pipe to which the cuspidor is secured, having a nozzle provided with lateral and alined discharge openings, the lateral opening being of less diameter than the extension of the cuspidor and projecting through said extension into the cuspidor, and the alined opening being valve-controlled.
2. The combination of a pipe having a lateral collared opening to which a cuspidor is adapted to be secured, a nozzle in the pipe 35 and having lateral and alined discharge openings, the lateral opening projecting into the lateral opening of the pipe, and a valve for controlling the alined opening of said nozzle.
40. 3. The combination of a pipe provided with a nozzle having a discharge opening in alinement with the pipe and a discharge opening at right angles to the pipe and projecting out through an opening of the same, a cuspidor having a cover and secured to the pipe with the lateral discharge opening of the nozzle projecting into the same, and a

manually operated valve for controlling the alined discharge opening of the nozzle.

4. The combination of a pipe provided with a nozzle having discharge openings at right angles one to the other, one of the openings being in alinement with the pipe and the other projecting laterally through an opening in the pipe, a cuspidor secured to the pipe around the lateral discharge opening of the nozzle, a valve in the discharge opening of the nozzle which is in alinement with the pipe, a crank shaft mounted in the pipe, a rod connected to the crank of said shaft and to the valve, and a handle for operating the crank shaft.

5. The combination with a pipe, of a plurality of cuspidors communicating with said pipe, a plurality of nozzles in said pipe, each having one branch communicating with one of said cuspidors and another branch for directing a fluid longitudinally through said pipe, and means whereby said nozzles may be controlled to direct a fluid flow through 70 said cuspidors and pipe, or through said pipe alone.

6. The combination of a pipe, a plurality of cuspidors connected with the pipe, a plurality of nozzles in the pipe, each having two 75 branches, one in alinement with the pipe and the other at right angles thereto and projecting into a cuspidor, connected valves for the alined branches of the nozzle, a spring connected with one valve, and means 80 connected with the other valve for operating the said valves.

7. The combination of a cuspidor having a raised cover provided with a central conical depending projection, a pipe to which the cuspidor is secured, and a nozzle in the pipe and discharging into the cuspidor.

In testimony whereof I have signed my name to this specification in the presence of two subscribing witnesses.

MAHLON DUFF GREEN.
